(57) **CLAIM**

We claim the ornamental design for a pet treat, as shown and described.

DESCRIPTION

FIG. 1 is a front, top and right side perspective view of a pet treat showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The break lines shown in the middle portion of the pet treat in FIGS. 1 and 4-7 indicate that the appearance of any portion of the article between the break lines forms no part of the claimed design.

The stippled shading and the line shading shown in FIGS. 1-7 represent a contrasting appearance.
